CLAIM

I claim the ornamental design for a portable video magnifier, as shown and described.

DESCRIPTION

FIG. 1 is a front and bottom perspective view of a portable video magnifier of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a top and front perspective view; and,

FIG. 9 is a top and rear perspective view with a stand shown in the upright position.
